UNITED STATES PATENT OFFICE.

OLIVER E. BARTHEL AND JOHN W. MCCREA, OF DETROIT, MICHIGAN.

FOOT CONTROL FOR AUTOMOBILES.

Application filed October 4, 1924. Serial No. 741,542.

To all whom it may concern:

Be it known that we, OLIVER E. BARTHEL and JOHN W. MCCREA, citizens of the United States, residing at Detroit, in the county of Wayne and State of Michigan, have invented certain new and useful Improvements in Foot Controls for Automobiles, of which the following is a specification, reference being had therein to the accompanying drawings.

This invention relates to foot pedals for the control of foot operable levers, rods and similar devices in automobiles where ordinarily the nature of such levers or devices tends to cause discomfort to the foot of an operator due to necessitating the foot being held in an unnatural position when actuating or when in readiness to actuate a lever or device, and where, due to foot weariness on the part of the operator or to the vibration of the automobile, undesirable pressure upon or actuation of the said lever or device is liable to occur with consequent interference with the proper control of the automobile.

For such purposes the use of pedals in the form of auxiliary foot plates rockably or hingedly mounted with the toe portion extending over the lever, rod or device to be operated thereby have been suggested, but although these devices do in some cases tend to cause the foot to assume a more nearly natural position which is more restful to the foot of an operator, they do not effectively overcome the tendency to exert pressure on the levers or devices at undesirable times such as when subjected to the influence of the vibration of the automobile.

It is, therefore, an object of this invention to provide a device which will meet these requirements in a very efficient manner and which will consequently facilitate the proper foot control of an automobile to which it is applied.

A further object is to provide for the resilient support of a foot pedal adapted for the control of a foot lever, rod or device, the said resilient support yieldingly tending to retain the said pedal in a normal inoperative position and to thereby support and relieve the strain upon the foot of an operator.

The invention further purposes to provide a device for the purposes set forth

wherein a foot pedal is hingedly mounted 55 approximate to the heel portion thereof, with the toe portion adapted to extend over a device to be operated thereby, and resilient means bearing upwardly against the underside of the said pedal. 60

Still further objects subsidiary to or resulting from the aforesaid objects, or from the construction or operation of the invention as it may be carried into effect, will become apparent as the said invention is 65 hereinafter further disclosed.

In carrying the said invention into effect, we may provide a foot pedal in the form of a foot-plate having hinged beneath the heel portion thereof a member or support which extends downwardly therefrom to the foot-board or other surface to which the device is to be attached, the said support having a base adapted to be secured to the said foot-board in any suitable manner, said base being extended forwardly and upwardly in the form of a plate spring toward the center or tread portion of the foot-plate and provided with adjustable means engaging the underside of the said 70 tread portion by the adjustment of which 75 means the resistance of the said spring to the depression of the said foot pedal may be increased or decreased. The foot pedal is adapted to be situated for use with the 75 toe portion thereof extending over or attached to a lever, rod or other device which 80 it is intended to operate, the arrangement being preferably such that the said foot 85 pedal when applied to an inclined foot- 90 board normally lies in a plane approximately parallel with the plane of the said foot-board whereby the foot of an operator may 95 be supported in an easy and natural position.

All of which is more particularly described and ascertained hereinafter, by way of example, having reference to the accompanying drawing, wherein

Figure 1 is a plan of a foot pedal constructed in accordance with the said invention, parts of the rubber facing thereof being broken away;

Figure 2 is a vertical longitudinal section of the same;

Figure 3 is an end elevation of the same;

Figure 4 is a side elevation of the said foot pedal;

Figure 5 is a fragmentary detail sectional illustration showing a modified form of the resilient foot-plate support;

Figure 6 is a fragmentary view, partly in section, of the foot-board and adjacent parts of an automobile having the improved foot pedal applied thereto and adapted to actuate the accelerator thereof; and

Figure 7 is a similar view to Figure 6, illustrating the application of the invention to the control of a clutch pedal.

Similar characters of reference indicate similar parts in the several figures of the drawing.

The foot pedal comprises a foot plate 1 provided at the heel end with a raised flange 2 for the positioning of the heel of an operator and in its intermediate portion with upwardly pressed abutments 3 adapted to prevent forward slipping of the heel on the said plate; and 4 is an upwardly extending lateral lug preventing side motion of the foot on the said foot-plate. The said foot-plate is recessed at 5 and 6 for the reception of non-slip rubber or other inserts 7 and 8. All of these features may however be varied to suit matters of taste, conveniences of manufacture or questions of expense as may be found necessary or desirable and are not regarded as essential to the invention.

Struck downwardly from the heel portion of the said foot-plate are lugs 9 which support the pintle 10 of a hinge 11 on the upper end of a support 12. This support preferably forms an integral part of a plate having a base 13, perforated at 14 whereby it may be attached by screws 15 to the floor-board 16 of an automobile, and also having a forwardly and upwardly extending portion 17 in the form of a plate spring, the outer end of which is provided with a bolt 18 passing therethrough, the head 19 of which bolt bears on the underside of the tread portion of the said foot plate.

20 and 21 are nuts by the manipulation of which the said bolt may be adjusted upwardly or downwardly in the member 17 and its bearing on the underside of the said foot-plate thereby varied so that the resistance of the spring member 17 to the depression of the said foot-plate may be increased or decreased to suit requirements and whereby also the normal elevation of the toe portion of the said foot-plate may be varied.

One of the principal applications of the said device is to an accelerator rod 22 as shown in Figure 6, whereby the resistance of the spring member 17 tends to prevent undesired pressure being exerted on the said accelerator rod, particularly due to vibration of the car, and a more even control of the automobile is thereby secured.

In Figure 7 the application of the device to a clutch pedal 23 is illustrated, the free end of the said clutch pedal being provided

with a pin 24 which works in the slot 25 of a slotted projection 26 on the underside of the toe portion of the pedal.

In this case the tendency which many drivers often experience to unconsciously press down the clutch pedal while driving and thereby more or less close the clutch and wear or burn the lining thereof is almost completely overcome, the advantages of resting the foot being also maintained as in connection with the application of the pedal to the operation of other levers, rods or devices.

In Figure 5 a substitute for the adjustable bolt 18 is indicated wherein a bolt 27 is illustrated having adjusting nuts 28 and 29, the bolt supporting a resilient button comprising a piston member 30 slidably housed in a hollow cylindrical casing 31 which encloses a compression spring 32, the upper surface of the said casing being domed to reduce the area of contact with the underside of the foot-plate. This spring 32 may either act in an auxiliary capacity to the member 17, or the member 17 in this case may be more or less rigid and the spring 32 form the sole or main yielding means for the said foot-plate as will be readily understood, but in the illustrated device Figure 5, the resiliency is mainly attained by the fact that the casing is in the form of an air enclosing dash pot.

It will be seen that the described arrangement includes a combination foot-plate, bracket and spring, wherein the foot-plate is adjustable for various heights of levers, rods or devices to which it is to be applied, and is subjected to spring tension to resist the effects of vibration and acts as a stabilizer to the device. In other words, the device comprises a resiliently mounted foot rest peculiarly adapted to the control of foot levers or similar devices in automobiles.

This invention may be developed within the scope of the following claims without departing from the essential features of the said invention, and it is desired that the specification and drawing be read as being merely illustrative and not in a limiting sense, except as necessitated by the prior art.

What we claim is:—

1. A device of the class described, comprising a foot-plate, a support hingedly secured to the rear part of said plate, stabilizing means yieldingly bearing on the underside of said plate forward of said support, and adjustable means varying the resilient elevation of said stabilizing means on said foot plate.

2. A device of the class described comprising a foot-plate, a support hingedly secured thereto, and vertically adjustable stabilizing means carried by said support and yieldingly bearing on the underside of said foot-plate forward thereof.

3. In combination with the foot lever of an automobile, a resiliently mounted foot rest operably engaging said lever, and adjustable means regulating the normal elevation of said foot rest.
4. In combination with the foot lever of an automobile, a resiliently mounted foot rest, a support attachable to the foot-board of such automobile mounting said rest operably engaging said lever, and adjustable means varying the elevation of the lever engaging end of said foot rest.
5. In a device of the class described, a foot plate, and means hingedly and resilient-

ly supporting said foot plate, said means comprising a single metallic member having its rear end bent upwardly to hingedly engage the heel portion of said foot plate, its intermediate portion being adapted to be secured to the foot board of an automobile and its forward end extended upwardly and forwardly to form a resilient support for the forward part of said foot plate, substantially as described.

In testimony whereof we affix our signatures.

OLIVER E. BARTHEL.
JOHN W. McCREA.
